ORNAMENTAL ELECTRIC LIGHT FIXTURE

William T. C. Desmond, West Orange, and William J. Desmond, Harrison, N. J., assignors, by direct and mesne assignments, to Noma Electric Corporation, New York, N. Y., a corporation of New York

Application May 7, 1948, Serial No. 25,558

4 Claims. (Cl. 240—52.4)

1

The invention relates to an ornamental electric light fixture constructed to simulate a candlestick and a holder therefor and which is adaptable for use as a Christmas tree light or as an ornamental lighting means for other purposes.

The main object of the invention is to provide an ornamental electric light fixture in the form of a candlestick and a hollow holder therefor and in which the candlestick portion is provided with a core made of a translucent plastic material with its upper end projecting from the upper end of the candlestick and shaped to simulate the flame of the candle, and in which the holder portion is made of a translucent material and is provided with an electric light bulb receptacle having a threaded base portion projecting outwardly from the base of the holder and a threaded electric light bulb receiving portion extending within the holder and having an electric light bulb mounted therein.

A further object is to provide an ornamental electric light fixture in the form of a candlestick and a hollow holder therefor, and in which the candlestick portion is made of a hollow translucent material provided with an inner core, also made of a translucent material, and having its upper end projecting from the candlestick portion and shaped to simulate the flame of the candle, and in which the hollow holder portion is made of a translucent material and is provided with an electric light bulb receptacle having a threaded terminal portion projecting from the bottom of the holder and an electric light bulb receiving portion projecting upwardly within the holder and with a light bulb mounted therein.

A further object is to provide a simple, inexpensive ornamental electric light fixture which is adapted for use for display lighting purposes such as for a Christmas tree light, a dressing table light, a light for shop windows, or for merchandise display counters.

Additional objects of the invention will appear more fully from the description hereinafter set forth.

For a better understanding of the invention reference is made to the accompanying drawing in which:

Figure 1 is a view in elevation of an electric light fixture constructed in accordance with the invention; and

Figure 2 is a central vertical section through the electric light fixture.

Referring more specifically to the drawing, the electric light fixture comprises a cylindrical hol-

2

low member 1 which may be made of an opaque plastic material or of a translucent colored plastic material and designed to simulate a candlestick. The lower end of said cylindrical hollow candlestick member 1 is adapted to be mounted, in any suitable manner, in an enlarged cylindrical hollow base portion 2 also made of a plastic material and which is centrally mounted upon a depressed portion of a dish shaped member 3 which forms the cover portion for a hollow oval shaped base supporting member 4, forming a holder for the candlestick member 1, and its base portion 2. The dish shaped cover member 3 is provided with a handle 5 which is secured to said cover member.

Mounted within the hollow cylindrical candlestick member 1, is a core 6, made of a translucent thermoplastic material such as "Lucite," or "Plexiglass," and which has its upper end 7, projecting above the top portion of the candlestick member 1, and shaped to simulate a flame for the candlestick member 1. The lower end 8, of said core may extend down to the base 9 of the candlestick member as shown in Figure 2 or it may extend below the base of the candlestick and so that it will project downwardly into the hollow base member 2 (not shown).

Mounted in the lower end of the hollow oval shaped base supporting holder 4, is an electric light bulb receptacle having an outer threaded portion 10 projecting from the bottom of the holder 4 and adapted to be screwed into a suitable sized electrical socket connected to an electrical supply source. The electric light bulb receptacle is also provided with the usual interior threaded portion adapted to receive the screw threaded base portion of an electric light bulb 11, said electric light bulb, when mounted with respect to the receptacle, being positioned so that it will extend upwardly within the hollow translucent base supporting holder 4 and will be adapted to illuminate said holder.

It will be readily apparent that when the outer threaded portion 10 of the electric light bulb receptacle is screwed into an electrical socket connected to an electrical supply source, the bulb 11 will light up and illuminate the hollow translucent holder 4 and that the light from said bulb will be transmitted upwardly through the translucent thermoplastic core 6 to the top portion thereof and will illuminate the same and the reduced tip 7 of said core will also be illuminated so that it will have the appearance of a flame for the candlestick 1. Also, if the candlestick member 1 above its base supporting member 2, is

made of a translucent plastic material it will also be illuminated by the light rays passing upwardly through the translucent core 6, and if the candlestick member is made of a colored translucent material a further pleasing illuminated effect will be produced thereby.

It will also be apparent that the electric light fixture of the invention may be used in the form shown in the drawing as a decorative lighting means for a Christmas tree by inserting the screw threaded base 10 thereof in the usual socket provided in a Christmas tree lighting cord and which is adapted to be strung through the Christmas tree. It may also be used as a decorative table lamp by screwing the said screw threaded base into an electrical socket mounted in a suitable base support, or it may be used for various other lighting purposes where a decorative lighting result is desired.

While we have shown an oval shaped hollow support member for the candlestick member having a dish-like cover portion 3, it is obvious that such support member may be given any desired contour or shape and be provided with any suitably designed cover member. Also while the electric light fixture is shown in the drawing as constructed in the form of a Christmas tree light consisting of a candlestick and a holder therefore, it will be understood that the novel features of the invention may be employed in other types of lighting fixtures without departing from the scope of the claims.

What is claimed is:

1. An electric light fixture comprising a hollow cylindrical member simulating a candle and having its lower end mounted in the upper end of an enlarged hollow cylindrical base member, said enlarged hollow cylindrical base member having a central circular opening extending through the top portion thereof of less diameter than that of the cylindrical candle member, a cylindrical rod member of less diameter than said hollow cylindrical candle member, and made of a transparent plastic material, centrally positioned within said cylindrical candle member, and having its upper end projecting above the top edge of said candle member and shaped to simulate the flame of a candle, and its lower end projecting downwardly into the central opening formed through the upper end portion of said enlarged hollow cylindrical base member, a hollow member forming a holder and a support for the enlarged cylindrical base member of said cylindrical candle member, and an electric light bulb receptacle mounted in said hollow support member provided with a threaded base portion which projects outwardly from the bottom of said hollow support member.

2. An electric light fixture comprising a hollow cylindrical member made of a translucent material and simulating a candle, and having its lower end mounted in the upper end of an enlarged hollow cylindrical shaped base made of a translucent material and having a central circular shaped opening extending through the top thereof of less diameter than that of the cylindrical candle member, a cylindrical solid rod member made of a thermoplastic material and of less diameter than said hollow cylindrical candle member, positioned so that it will extend through the hollow candle member and with its upper end extending above the top thereof and its lower end extending downwardly through the

central opening in the top of said cylindrical shaped base, and a hollow member forming a holder and a support for the enlarged base for the candle member, said hollow supporting member having an electric light bulb receptacle mounted therein and provided with an outer threaded base portion which projects through the base of said hollow supporting member.

3. An electric light fixture comprising a hollow cylindrical member simulating a candle and having its lower end mounted in the upper end of an enlarged hollow cylindrical shaped base member, said cylindrical shaped base member having a central opening through the top portion thereof of less diameter than said hollow cylindrical member, a cylindrical solid rod member made of thermoplastic material extending through said hollow cylindrical candle member and having its upper end extending above the top thereof and shaped to simulate the flame of a candle, and its lower end mounted in and extending downwardly through said central opening of the enlarged cylindrical base member, a hollow support member made of translucent material and upon which said enlarged cylinder base member is mounted, an electric light bulb receptacle mounted within said hollow support member and having a screw threaded base portion projecting from the bottom of said support member and an electric light bulb mounted in said electric light bulb receptacle.

4. An electric light fixture comprising a hollow cylindrical member simulating a candlestick and made of an opaque plastic material, an enlarged cylindrical hollow support member for said cylindrical candlestick member having an opening through the top thereof of less circumference than said candlestick member, a cylindrical member made of a solid translucent material and of a less diameter than that of the candlestick member and positioned within the candlestick member with its upper end extending above the top thereof and its lower end positioned in the opening in the top of the enlarged cylindrical hollow support for said hollow cylindrical candlestick member and so it will project downwardly into the hollow portion of said member, and a hollow translucent support member for said enlarged support member for the candlestick member simulating in design a holder for a candlestick, said translucent support member having an electric light bulb receptacle mounted therein with an electric light bulb inserted therein and projecting upwardly into said support member and adapted to illuminate said support member and the solid cylindrical member positioned within the candlestick member.
